Marks F. Paskes, New York, N. Y.

Application May 17, 1950, Serial No. 10,006

Term of patent 14 years

(Cl. D58—26)

To all whom it may concern:

Be it known that I, Walter S. Fuld, a citizen of the United States, residing at the city, county, and State of New York, have invented a new, original, and ornamental Design for a Pouring Attachment for Containers, of which the following is a specification, reference being had to the accompanying drawing, forming part thereof.

Figure 1 is a top plan of a pouring attachment for containers, showing my new design;

Figure 2 is a top plan of said attachment with the parts in another position;

Figure 3 is an end view thereof with the parts in the positions shown in Figure 1;

Figure 4 is a side view of the same, with the parts in the positions shown in Figure 2; and

Figure 5 is another side view with the parts in the position shown in Figure 1.

I claim:

The ornamental design for a pouring attachment for containers, as shown.

WALTER S. FULD.
